UNITED STATES PATENT OFFICE.

WILLIAM C. H. WEFEL, OF EDGEWATER, COLORADO; CARA M. WEFEL ADMINISTRATRIX OF SAID WILLIAM C. H. WEFEL, DECEASED.

SIGNALING SYSTEM FOR STREET RAILWAYS.

Application filed September 22, 1925. Serial No. 57,851.

My invention relates to a signaling system for street railways and its primary object is to provide by a simple arrangement of co-operatively associated electrical devices, an effective and reliable means for announcing by visual or/and audible signals, the approach of a car on an electrical railway, at points remote from the track. Another object of the invention is to combine with the signaling device, an advertising feature which adds to the attractiveness and commercial value of the system and further objects reside in details of construction and a novel arrangement of parts as will be fully disclosed in the course of the following description made with reference to the accompanying drawings.

In the drawings in the several views of which like parts are similarly designated—

Figure 1 represents a diagrammatic plan view showing the application of my invention to the tracks of a street railway system at the intersection of two streets;

Figure 2, a perspective view of the annunciator of the system;

Figure 3, a front elevation of the annunciator drawn to an enlarged scale, together with the relay element of the invention, showing diagrammatically the circuits by which the members of the annunciator are energized in the operation of the system; and

Figure 4, a reduced section taken on the line 4—4, Figure 3.

Referring further to the drawings, 5 designates in Figure 1, the two tracks of a double track electric street railway laid parallel along a street 6 defined by sidewalks 7. The street along which the tracks extend intersects another street 8 at right angles and at a corner of the two streets is a store-building 9 which represents the station at which the signals conveyed by the system are announced.

The elements comprised in the system are an annunciator 10 placed in a conspicuous position in the station, a relay 12 mounted at any convenient place such as one of the poles 13 used for the suspension of the overhead trolley wires 14 of the electric-railway, and a contact-device 15 on one of the trolley wires which is adapted to complete a circuit by the engagement of the trolley on a car 16 passing the spot at which it is applied.

The relay 12 consists of a solenoid coil 17

which has its ends connected by means of conductors 18 and 19 respectively with the contact device 15 on the trolley wire 14 and with the ground as represented at 20.

The core 21 of the solenoid has an insulated connection with a resilient contact blade 22 fastened at one end for vertical reciprocation and adapted to engage at its opposite end with a relatively stationary contact-point 23.

A fuse 24 is connected in the conductor 18 for the usual purpose and the entire mechanism is enclosed in a box 25 which is fastened to the pole 13 of the railway or other suitable support.

The annunciator 10 is composed of a box or casing 26 of artistic design, the hinged front 27 of which has two openings formed one above the other. The lower opening 28 extending across the width of the box, is covered by a translucent plate 29 preferably made of frosted or stained glass upon which is painted an advertisement or other announcement in characters adapted to be prominently displayed when the glass is illuminated on the inside of the casing. The other upper opening 30 in the front of the box is round and comparatively small and it is covered by a lens 31 preferably made of glass of red or other conspicuous and noticeable color.

Mounted inside the box 26 is a lamp socket 32 for the disposition of an incandescent lamp 33 opposite to the opening covered by the lens 31, two similar sockets 34 for lamps 35 of greater strength placed opposite to the opening in the front of the box, covered by the glass pane 29, an electric alarm disposed between the two lamps and including a gong 36 and a sounding mechanism energized by current flow through a coil 37, and an electro-magnetic circuit breaker composed of a solenoid 38 the core 39 of which is connected with an insulated resilient contact blade 40 normally engaging with a fixed contact point 41.

The blade is fastened at one end to flex under stress and it is adapted to engage at its opposite end with a second stationary contact point 42 when moved by energization of the solenoid.

A dash-pot 43* connected at the other end of the solenoid core retards the return movement thereof for the purpose of maintaining the blade 40 and the contact point 42 in

current-transmitting proximity during a predetermined period of time.

The annunciator is connected in a lighting circuit the line wires 43 and 44 of which are 5 connected to binding posts 45 and 45^a in the box, and the solenoid-switch functions in the 10 operation of the system to control the path of current to the lamp socket 32 as one unit or to the lamp sockets 34 and the alarm coil 15 37 as another unit by the current flow 15 through the circuit controlled by the relay 12. The blade 22 and the contact point 23 of the latter are to this end connected by means of conductors 52 and 53 respectively 20 with binding posts 46 and 46^a in the box of the annunciator for connection with the operating circuits of the annunciator as will now be described.

The two lamp sockets 34 are connected in 25 multiple in a circuit of the electric lighting system which includes, commencing with the binding post 45, a conductor 51 branched at the point 55 into two lines 56 and 57 each including a filament of one of the two lamps 35 in the socket 34 and meeting in the contact point 41 of the switch, and a conductor 48 by which the movable contact member 40 of the switch is connected with the binding post 45^a.

30 It follows that under normal conditions the two lamps are incandescent by a flow of current which commencing at the pole of the source of electricity of the electric lighting system, connected with the binding post 45, 35 includes as shown by the full line arrows in Figure 1, the conductor 51 and its branches 56 and 57 including the filaments of the two lamps 35, the stationary contact point 41 normally engaged by the blade 40, the contact blade 40, and the conductor 48 which by medium of the binding post 45^a is connected with the opposite pole of the source of electricity of the lighting circuit.

A second circuit receiving its current 45 from the lighting circuit, is completed in the solenoid switch when by energization thereof, the blade 40 is moved into contact with the point 42, said second circuit including a wire 50 connecting the binding post 45 with the contact point 42 and including the filament of the lamp 33 in the socket 32, and the conductor 48 of the first described circuit.

The third circuit of the system controlled 50 in the relay 12 causes the energization of the coil 39 of the solenoid switch and the coil 37 of the alarm by current derived from the electric lighting circuit and inasmuch as the second circuit is normally open and controlled by the solenoid switch, it follows that when the third circuit is completed in the relay the alarm will be sounded and the lamp 33 incandescent at the same time while the circuit of the lamps 35 is open.

55 The third circuit includes commencing in

the source of the lighting circuit, the line wire 44, the binding post 45, the before mentioned conductor 48, a conductor 49 connected therewith in the fastening of the blade 40, the binding post 46, the wire 52, 70 the blade 22 of the relay-solenoid, the contact point 23 engaged by the blade when the solenoid is energized, the wire 53, the binding post 46^a, a conductor 58 in which is included the coil 39 of the switch of the annunciator, the windings of the alarm magnet 37, a wire 54 connecting the windings of the magnet 37 with the branch wire 57, the conductor 51, the binding post 45, and the line wire 43 of the lighting circuit. 75

Having thus described the construction and electrical connections of the elements comprised in the system, its operation will be readily apparent.

The annunciator 10 is installed in a corner drug store, a waiting room or any other place of shelter in convenient proximity to the corner or station at which the cars moving on one of the railway tracks, stop to receive and discharge passengers, and the contact device 15 is placed on the trolley wire above the track at a distance sufficiently far from the room in which the annunciator is installed to permit persons waiting in said room, to reach the stopping place in plenty 85 of time to board the car after the annunciator has announced the approach thereof owing to the engagement of the trolley on the car with the contact device on the overhead wire 14. 90

In most instances, the use of a relay is essential since the cars usually operate by direct current of from 500 to 600 volts, and the fire-regulations of cities or towns do not permit of bringing a current of that voltage 95 into a building with but very few exceptions.

The ordinary lighting circuit usually carrying an alternating current of from 110 to 120 volts is therefore preferably employed for the operation of the annunciator 10 in which case the relay functions to energize the annunciator switch when the relay circuit is closed by the engagement of the trolley on the approaching car with the contact device 15. 110

As stated hereinbefore, the circuit in which the lamp sockets 34 are connected is normally closed so that under ordinary conditions the lamps 35 incandesce to illuminate the translucent advertising plate at the 115 front of the annunciator box.

When the trolley on an approaching car engages the contact device on the respective overhead wire, the relay circuit is closed with the result that the blade 22 is by movement of the core 21 of the solenoid 17, brought into engagement with the contact point 21 which closes the circuit of the solenoid coil 39 and the windings of the alarm magnet of the annunciator. The alarm is 125 130

thus sounded to audibly apprise the waiting persons of the approach of the car, and the energization of the solenoid switch at the same time causes the circuit of the lamps 35 to be opened and that of the lamp 33 to be closed so that the exclusive illumination of the red lens 31 will give a visible indication of the fact that the car will reach the stopping point within the predetermined period.

10 It will be understood that one or the other of the two indicating appliances of the annunciator may be eliminated although under ordinary conditions their joint actions are desirable, and that other variations in the 15 construction and arrangement of the elements of the system may be resorted to without departing from the spirit and scope of the invention.

20 The system installed in the manner herein described, is of great benefit to the travelling public particularly in cold and stormy weather since it permits of the travellers remaining under shelter without fear of missing their car, until almost the very time at 25 which the car reaches the stopping point, and the invention is furthermore of benefit to a store in which the annunciator is located because of the opportunity presented for purchases by the persons waiting for the 30 cars.

What I claim and desire to secure by Letters Patent is:—

1. A system of the character described comprising a railway, a circuit, means for closing the circuit by a car passing a determinate point on the railway, a relay-switch in the circuit, a source of electricity, and an annunciator including an illuminating unit in a normally closed circuit with the source, an indicatory unit in a normally open circuit with the source, and a magnetic switch in circuit with the relay-switch, controlling the circuits of the two units to reverse the condition thereof when the circuit of the relay-switch is closed by the car.

2. A system of the character described comprising a railway, a circuit, means for closing the circuit by a car passing a determinate point on the railway, a relay-switch in the circuit, a source of electricity, and an annunciator including an illuminating unit in a normally closed circuit with the source, an indicatory unit in a normally

open circuit with the source, a magnetic switch in circuit with the relay-switch, controlling the circuits of the two units to reverse the condition thereof when the circuit of the relay-switch is closed by the car, and an alarm in the circuit in which the two switches are connected.

3. A system of the character described comprising a railway, a circuit, means for closing the circuit by a car passing a determinate point on the railway, a relay-switch in the circuit, a source of electricity, and an annunciator including an illuminating unit in a normally closed circuit with the source, an indicatory unit in a normally open circuit with the source, a magnetic switch in circuit with the relay-switch, controlling the 70 circuits of the two units to reverse the condition thereof when the circuit of the relay-switch is closed by the car, and a dash-pot to retard the return movement of the magnetic switch after the circuit in which it is connected with the relay-switch, is reopened.

4. A system of the character described comprising a railway, a circuit, means for closing the circuit by a car passing a determinate point on the railway, and an annunciator including a box having an advertising plate and a signal lens, a lamp to illuminate the advertising plate, in a normally closed circuit, a second lamp to illuminate the signal lens, in a normally open circuit, 85 and a magnetic switch controlling the lamp circuits, connected to be energized by closing of the first mentioned circuit by the car.

5. A system of the character described comprising a railway, a circuit, means for closing the circuit by a car passing a determinate point on the railway, and an annunciator including a box having an advertising plate and a signal lens, a lamp to illuminate the advertising plate, in a normally 90 closed circuit, a second lamp to illuminate the signal lens, in a normally open circuit, a magnetic switch controlling the lamp circuits, connected to be energized by closing of the first mentioned circuit by the car, and 100 an alarm connected to be energized upon energization of the magnetic switch.

In testimony whereof I have affixed my signature.

WILLIAM C. H. WEFEL.

Certificate of Correction.

It is hereby certified that the name of the administratrix in Letters Patent No. 1,603,257, granted October 12, 1926, upon the application of William C. H. Wefel, of Edgewater, Colorado, for an improvement in "Signaling Systems for Street Railways," was erroneously written and printed as "Cara M. Wefel," whereas said name should have been written and printed as *Clara M. Wefel*, as shown by the records of assignments in this office; and that the said Letters Patent should be read with this correction therein that the same may conform to the record of the case in the Patent Office.

Signed and sealed this 9th day of November, A. D. 1926.

[SEAL.]

WM. A. KINNAN,
Acting Commissioner of Patents.
